HOUSING FOR A RADIO-PHONOGRAPH OR SIMILAR ARTICLE

Harvey K. McQuarrie, Kitchener, Ontario, Canada, as-
signor to Electrohome Limited, Kitchener, Ontario,
Canada

Filed June 18, 1971, Ser. No. 154,712

Term of patent 14 years

Int. Cl. D14—03

U.S. Cl. D56—4

FIG. 1

FIG. 2

FIG. 1 is a left side, top and front perspective view of a housing for a radio-phonograph or similar article, showing my new design;

FIG. 2 is a top plan view;

FIG. 3 is a front elevational view;

FIG. 4 is a side elevational view, the opposite side being substantially a mirror image thereof; and

FIG. 5 is a fragmentary rear elevational view thereof.

Portions of the drawing figures are shaded to indicate contrast in appearance, and portions are diagonally lined to indicate transparency.

I claim:

The ornamental design for a housing for a radio-phonograph or similar article, as shown and described.
